UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 24,373, dated June 11, 1895.

Application filed October 29, 1894. Serial No. 527,354. Term of patent 7 years.

To all whom it may concern:

Be it known that I, JOHN B. MORGAN, a citizen of the United States, residing in Philadelphia, Pennsylvania, have invented a certain Design for Ticking and other Woven Fabrics, of which the following is a specification.

My design for ticking or other woven fabric is clearly illustrated in the accompanying drawing.

The essential feature of the design is the arrangement of the alternate wide and narrow stripes, each stripe having well defined supplementary stripes. The wide stripe P is composed of a series of dark supplemental stripes *p*, alternating with a series of light stripes *p'*. Each dark stripe is bordered on one side by a tinted stripe *p*². The narrow stripe Q is composed of two well defined dark stripes *q* and a central light stripe *q'* and on one side of each dark stripe *q* is a tinted

stripe *q*². The tint of the background is carried through the stripes P and Q as clearly illustrated in the drawing.

I claim—

The design for woven fabric consisting of alternate wide and narrow stripes, each wide stripe composed of a series of dark supplemental stripes alternating with light stripes, with tinted stripes bordering the dark stripes, the narrow stripes composed of two well defined dark stripes, a central light stripe and tinted stripes, as herein described and illustrated in the accompanying drawing.

In testimony whereof I have signed my name to this specification in the presence of two subscribing witnesses.

JOHN B. MORGAN.
